(No Model.)

C. W. SUMMERSKILL.
FIRE ALARM OR FIRE AND HEAT INDICATOR.

No. 439,441.

Patented Oct. 28, 1890.

Charles William Summerskill

UNITED STATES PATENT OFFICE.

CHARLES WILLIAM SUMMERSKILL, OF HOCKLEY HEATH, ENGLAND.

FIRE-ALARM OR FIRE AND HEAT INDICATOR.

SPECIFICATION forming part of Letters Patent No. 439,441, dated October 28, 1890.

Application filed July 15, 1890. Serial No. 358,811. (No model.)

To all whom it may concern:

Be it known that I, CHARLES WILLIAM SUMMERSKILL, of Hockley Heath, England, a subject of the Queen of Great Britain, have invented a certain new and Improved Fire-Alarm or Fire and Heat Indicator; and I do hereby declare that the following is a full, clear, and exact description of the invention, which will enable others skilled in the art to 10 which it appertains to make and use the same.

My invention has for its object, principally, to give an alarm when a fire occurs in a room or place where my said invention is fixed, but 15 is also applicable to the giving of an alarm when the room or place where it is fixed attains a temperature exceeding the maximum temperature which it is desired the said room or place shall have.

20 My said invention consists of the following construction and arrangement of parts: I take a flat closed chamber or vessel made of thin elastic sheet metal or alloy, filled with air or other elastic fluid, the said chamber 25 being preferably circular and having one or both of its sides corrugated with circular concentric corrugations. To the center of the corrugated side, or one of the corrugated sides, of the said flat closed metallic chamber and 30 at right angles thereto I fix a metallic rod, the said rod being in the line of the axis of the chamber. In line with the said rod is another adjustable metallic rod capable of approaching to or receding from the first-named 35 rod by a screwing motion. I will call this rod the "screwed rod." The parts described are supported by a framing, the screwed rod being electrically insulated from the closed metallic chamber and its axial rod. The said 40 chamber is supported at its periphery. When the parts are at an ordinary temperature, the end of the screwed rod is not in contact with the end of the axial rod of the closed chamber. When, however, an abnormal temperature 45 in the room or place where the instrument is situated is attained, the air in the closed chamber is expanded, the side or sides of the said chamber become bulged, and the axial rod thereby moved toward the screwed 50 rod, and by the adjustment of the screwed rod the end of the axial rod of the chamber

may be made to come into metallic contact with the end of the screwed rod at any required temperature.

I avail myself of the action described to 55 produce an alarm in the following manner: The conducting-wires from a voltaic battery or other source of an electric current are connected, respectively, to the axial rod and the screwed rod, the said rods being thus made 60 the respective electrodes of the voltaic battery. When the instrument is at ordinary temperatures, these electrodes are separated from each other. When, however, the chamber is sufficiently heated to advance the axial 65 rod so far as to bring its end into electrical contact with the screwed rod, the electric circuit is completed and an electric current flows through the wires and parts forming the completed circuit. In this circuit is an electro- 70 magnet, which is excited on the completion of the current, and the said magnet acting on an armature may be made to ring a bell or put into operation signals of various kinds, as is well understood.

75 I will now proceed to describe with reference to the accompanying drawings the manner in which my invention is to be performed.

Figure 1 represents in front elevation, Fig. 2 in side elevation, and Fig. 3 in back elevation, a fire-alarm or fire and heat indicator the parts of which are constructed and arranged according to my invention. Fig. 4 represents a cross-section of the same taken on the line a a of Fig. 2, and Figs. 5 and 6 represent 80 cross-sections of the same taken in a plane at right angles to that in which the section Fig. 4 is taken. The section Fig. 5 is taken on the line b b, Figs. 1 and 4, through one of the terminals, and the section Fig. 6 is taken 85 on the line c c, Figs. 1 and 4, through the other terminal. Fig. 7 represents a modified arrangement of the dial and pointer.

90 The same letters of reference indicate the same parts in the several figures of the drawings.

95 d is the circular wooden framing supporting the several parts of the apparatus, and e e are the flat closed chambers or vessels, made of thin elastic metal or alloy, filled with air, 100 the said chambers e e being soldered together at their centers, the sides of the said chambers

being corrugated with concentric corrugations, as represented. Instead of two closed chambers a single chamber, or more than two chambers, may be used, and when two or more chambers are used they need not open into one another, but constitute independent chambers.

10 *f* is a metal casing or box soldered to the edge of the outer chamber, and the said casing *f* is secured by screws to the ebonite disk *g* within the casing *d*. The ebonite disk is made in two pieces with distance tubes or pillows between them.

15 In the line of the axis of the two chambers *e e* and on the inner chamber a metallic rod *h* is fixed, which rod as the chambers expand is moved inward or in the direction of the back of the apparatus.

20 *k* is the adjustable metallic rod, situated in the line of the axial metallic rod *h*, carried by the chambers *e e*. This second or screwed rod *k* works in a screwed hole in the axis of the ebonite disk *g*, so that the said screwed rod is electrically insulated from the closed 25 metallic chambers *e e* and their rod *h*. The rear end of the screwed rod *k* carries a pointer or index-finger *l*, which traverses the circular graduated dial or scale represented at the back of the apparatus. By turning the said 30 screwed rod *k* by its pointer *l*, the adjustment of its inner end nearer to or farther from the metallic rod *h*, so as to bring the apparatus into operation at any required temperature, can be effected, the position of the screwed 35 rod being indicated by the position of the pointer *l* on the graduated dial or scale—that is to say, if the apparatus is required to be brought into operation when the room or place in which it is used attains a temperature of 100° Fahrenheit, the screwed rod *k* has the position with respect to the axial 40 rod *h* represented.

45 Should the apparatus be required to be brought into operation when the room or place attains a higher or lower temperature than that supposed, the pointer *l* is turned on the dial or scale to the right or left and brought opposite the required figures on the scale, so as thereby to increase or diminish 50 the distance between the end of the adjustable screwed rod *k* and the axial rod *h* on the closed chambers. Thus by driving home the screwed rod *k* more or less the apparatus may be adjusted with the greatest nicety to 55 give an alarm at any required temperature in the manner hereinafter described.

60 When the apparatus is fixed with its back against a wall or other surface, as herein-after described, the dial and pointer are pro-65 tected and cannot be tampered with without removing the apparatus; or, the dial may be arranged on the periphery of the outer casing *d*, and the end of the pointer *l* be bent at right angles to work over the said periphery, as represented in Fig. 7. I prefer, however, the first-described arrangement of the dial and pointer.

On the supporting-framing *d* of the apparatus are two terminals *m p*, to which the conducting-wires from a voltaic battery or other source of an electric current are connected, and the two terminals *m p* are connected, respectively, to the axial rod *h* and the screwed rod *k* in the following manner: The way in which the axial rod *h* is connected to the terminal *m* is seen in Fig. 5. The metallic casing *f* of the chambers is connected in part to the insulating-disk *g* by the long screw *q*. To the inner end of the said screw *q* a connecting-wire *r* is secured, which 70 wire passes through the outer supporting-framing *d* and is connected to the terminal *m*. The manner in which the screwed rod *k* is connected to the other terminal *p* is seen in Figs. 4 and 6. On the adjustable screw *k* 75 is a disk to which one end of the spring-connecting wire *s* is soldered, the said disk having an axial screwed hole in which the screw *k* works, as shown. The said spring-wire *s* is bent in the manner seen in Fig. 4, and its 80 upper end bears against the screw-pin *t*. A second and thin wire *u* is fixed to the pin *t*, and passing through the framing *d* is secured to the screw of the terminal *p*. The two rods *h k* are thus made the respective electrodes 85 of the voltaic battery or other source of an electric current. Instead of employing the disk to which the spring-wire *s* is soldered for establishing an electrical continuity with the screw *k*, a thin metallic ribbon may be used 90 in place of the wire *s*, which ribbon may be coiled several times around the screw *k*, its inner end being soldered to the said screw *k*. The disk represented on the screw *k* is in this 95 case dispensed with and an unbroken metallic continuity established between the pin *t* and the screw *k*. In all cases where it is 100 practicable the metallic connections or junctions described and represented in the electric circuit are perfected by being soldered. 105

The action of my new or improved fire-alarm or fire and heat indicator is as follows: When the instrument is at ordinary temperature, the ends *h k* of the electrodes of the voltaic battery are separated from each other, 110 as represented in Figs. 5 and 6. Should the room or place in which the apparatus is situated become sufficiently heated, the closed metallic chambers *e e* expand by the expansion of the air in them, and their corrugated 115 sides become bulged, and the axial rod *h* is so far advanced as to bring its end into electrical contact with the end of the screwed rod *k*. The electric circuit is thereby completed 120 and a voltaic or electric current flows through the said rods *h* and *k* and their connections and the wires joined to the terminals *n* and *p*, forming the completed circuit. In this circuit is an electro-magnet, which is excited on the completion of the circuit, and the said 125 magnet acting on an armature may be made to ring a bell or put into operation signals of various kinds. In this way an alarm is given 130 when the room or place where the apparatus

is fixed attains a temperature higher than that which it is desired the said room or place shall have.

In order to prevent any failure by corrosion or oxidation of electrical contact between the ends of the rod *h* and screw *k*, I tip or coat the said ends with gold or platinum or other metal or alloy which does not oxidize by exposure to the air, and as the contact-points are in a practically air-tight chamber they are prevented from being coated with any deposit from the air which might impair their efficiency. By these means the passage of an electric current is secured whenever the end 15 of the rod *h* is brought into contact with the end of the rod *k*.

In fixing my invention in the room or place where it is to be used, it may be attached to any wall or surface by means of the ear *x* at 20 the top of the frame, as represented in Figs. 1, 2, and 3, the said ear having a hole in it through which a screw or nail may be passed.

I prefer to employ the instrument or apparatus constituting my invention in pairs, so 25 that if by accident or otherwise one of the

instruments shall become disabled the other may give the required signal in the manner hereinbefore described. I also consider it a desirable precaution to examine or test the instruments at regular intervals—say of a 30 week or a month—in order to ascertain if they are in working order.

Having now particularly described and ascertained the nature of my invention and the manner in which the same is to be performed, 35 I declare that I claim as my invention—

In a thermostat, the combination of the in-closing-casing *d*, the air-tight expansible chambers *e*, the contact-rod *h* thereon, the screwed rod *k*, in axial line with the rod *h*, the 40 terminals *m p*, one connected with the chambers *e* and the other with a screw *t* in the casing, a disk in threaded engagement with the rod *k*, and a spring-arm *s*, soldered to said disk and bearing against the screw *t*, all operating substantially as described. 45
